UNITED STATES PATENT OFFICE.

JACKSON M. ROE, OF SUNNYSIDE, WASHINGTON, ASSIGNOR OF ONE-HALF TO JOHN ALEXANDER, OF SUNNYSIDE, WASHINGTON.

AUTOMATIC TRAIN-STOPPING APPARATUS.

1,089,267.

Specification of Letters Patent.

Patented Mar. 3, 1914.

Application filed May 20, 1913. Serial No. 768,785.

To all whom it may concern:

Be it known that I, JACKSON M. ROE, a citizen of the United States, residing at Sunnyside, in the county of Yakima and State of Washington, have invented new and useful Improvements in Automatic Train-Stopping Apparatus, of which the following is a specification.

This invention relates to improvements in automatic train stopping apparatus and has particular application to an electrically operated apparatus of this character.

In carrying out the present invention, it is my purpose to provide an automatic train stopping apparatus whereby a train entering the danger zone will be automatically brought to a gradual standstill so that the transmission of shocks and jars to the various cars of the train, incident to such train being brought to a sudden standstill, will be eliminated thereby obviating unnecessary wear on the equipment and reducing the cost of maintenance to normal.

It is also my purpose to provide an apparatus of the type set forth which will embody among other features, a resistance grid including a plurality of resistance sections connected in series located on the roadway and capable of swinging movement and a train carried mechanism composed of a source of energy and a shoe adapted to ride over the resistance grid when the latter is elevated or in active position, a controller being also included in the train carried mechanism and connected with such shoe and source of energy, in series with an electric circuit whereby when the grid is in active position, the shoe will ride over the same and gradually cut the resistance out of the circuit so that the controller will operate gradually and bring the train to a stop.

Furthermore, I aim to provide an apparatus of the character described wherein by means of a number of contact fingers arranged along the trackway and appropriately spaced apart and adapted to be swung to an active position simultaneously, and a train carried mechanism including a shoe adapted to engage the contact fingers successively when such fingers are in active position, a source of energy, and a controller, and an electric circuit including said fingers,

shoe, source of energy, and controller, the controller will be energized in such manner as to bring the train to a standstill gradually when such train passes over the active contact fingers.

With the above and other objects in view, the invention consists in the construction, combination and arrangement of parts hereinafter set forth in and falling within the scope of the claims.

In the accompanying drawings, Figure 1 is a diagrammatic view of a track portion of my improved train stopping apparatus. Fig. 2 is a similar view of the train carried mechanism of the apparatus. Fig. 3 is a longitudinal sectional view of the controller, parts being shown in elevation. Fig. 4 is a sectional view through the valve in the train line air pipe and under the influence of the controller. Fig. 5 is a cross sectional view through the casing of the resistance grid, one of the contact fingers of such grid being shown in elevation. Fig. 6 is a cross sectional view through the operating device for throwing the resistance grid to active position.

Referring now to the accompanying drawings in detail, the numerals 1, 1 designate parallel lines of rails of a trackway. Arranged between the lines of rails 1, 1 of the trackway and disposed longitudinally thereof is a resistance grid composed, in the present instance, of a longitudinal shaft 2 having each end thereof journaled within a bearing carried by one side wall of a casing 3. Fixed to the shaft 2 and insulated therefrom as at 4 are collars 5 appropriately spaced along the length of the track and provided with tangentially extending contact fingers 6 each adapted to normally lie within a casing 7 resting upon the ground and having the shaft passed through the opposite side walls adjacent to one end thereof. In the present instance, each finger 6 carries on the under side thereof a resistance section or coil 8 having one terminal tapped onto the respective finger and the opposite end fastened to the next adjacent finger, the sections of resistance decreasing progressively in size from one end finger to the other in the direction of traffic as indicated by the arrow in Fig. 1 of the drawings,

the section of resistance connected to the last finger being tapped onto one line of rails as at 9. The sections of resistance 8 together with the fingers constituting a resistance grid which may be elevated to active position or lowered to an inactive position according to the movement of the shaft 2.

In the present instance, the operating mechanism for the shaft comprises a solenoid magnet 10 disposed below each casing 3, and having the core 11 thereof extending into the casing through the lower wall thereof and connected through the medium of a link 12 with the free extremity of an arm 13 keyed upon the respective end of the shaft 2, the solenoid magnets being connected in series in an electric circuit composed of a conductor 14, a portion of the line of rails 1 opposite from that to which the resistance grid is tapped onto, and a conductor 15 tapped onto such line of rails. This solenoid circuit in the present instance, is controlled by a manually operable switch 16 located in the train despatcher's office or at some other suitable point. It will be understood, however, that the switch may be in the form of an automatic circuit closer connected up to the signal blades or semaphore of the train controlled block signal system of the railway, as will be readily understood by those skilled in the art, so that when the block signal is at danger the circuit through the solenoids will be closed and the resistance grid thrown to an active position.

The train carried mechanism of my improved stopping apparatus comprises, in the present form of my invention, a source of energy as a battery 17, a contact shoe 18 carried by the bottom of the locomotive or other car and adapted to ride over and engage the fingers 6 when the grid is in active or elevated position, and controller 19 composed, in the present instance, of a solenoid magnet 20 having the core 21 thereof formed at the outer end with an outwardly extending shank 22 carrying a pin 23 disposed within a slot 24 formed in the free extremity of a lever 25 connected to the stem of a valve located in the train line air pipe and adapted when the solenoid is energized to bleed the train line air and so effect an application of the brakes to the wheels. In the present instance, the valve under the influence of the controller 19 comprises a casing 26 connected in the train line air pipe at diametrically opposite points as at 27, 27 and having the inner wall thereof cut out as at 28 contiguous the outlet or discharge side of the casing and a semicircular turn plug 29 rotatably mounted within the casing and having the stem thereof connected to the lever 25 and adapted when rotated to permit a gradual escape of air, the turn plug 29, in the opening of the valve, establishing communication

between the main air reservoir and the atmosphere by way of the train line air pipe and the cut away portion 28 of the valve casing to effect a service application and in its continued movement establishing a direct path for the train line air to the atmosphere so as to bring about, in effect, an emergency application. The shoe 18, source of energy 17, and the controller 19 are connected in series in an electric circuit including a conductor 30 having one terminal tapped onto the shoe 18 and the opposite end connected to one side of the battery 17, a conductor 31 leading from the opposite side of the battery through the coil of the solenoid magnet 20 and tapped onto the axle of the car, a portion of the respective line of rails 1 and the resistance grid back to the shoe.

In the present instance, an air cylinder 32 is suitably fastened to the rear end of the solenoid magnet 20 and is provided with a plunger 33, the rod 34 of which is fastened to the inner end of the core 21 of the solenoid so that when the core is drawn inwardly under the action of the magnet to open the valve and bleed the train line air pipe, the air within the cylinder will be compressed to counteract the inward pull of the magnet.

From the foregoing description taken in connection with the accompanying drawings, the construction, mode of operation and manner of employing my invention will be readily apparent. Assuming the circuit of the solenoids for operating the shaft 2 to be closed at the switch 16, it will be seen that rotary movement will be transmitted to the shaft 2 through the medium of the cores 11, links 12 and arms 13 with the effect to elevate the fingers 6 carrying the sections of resistance 8 thereby disposing such fingers in the path of the shoe 18 on an approaching train. When the train rides over the active fingers the shoe 18 thereon contacts with such fingers and so completes the circuit to the magnet 20 of the solenoid of the controller, current in such circuit flowing from one side of the battery 17 through the conductor 31, the coil of the magnet 20 of the controller, the respective axle and wheel of the car, a portion of the line of rails 1, the sections of the resistance grid and back to the other side of the battery by way of the shoe 18 and conductor 30. When the shoe 18 contacts with the first finger all of the resistance sections are in circuit with the battery and as a consequence, the solenoid 20 does not receive the full strength of the current so that the core 21 moves into the solenoid magnet such a distance that the reduction of the train line air pressure, incident to the opening of the valve, is unappreciable so far as bringing the train to an immediate stop is concerned, the air within the cylinder 32 and compressed by the plunger 33 de-

termining the distance that the core 21 moves into the magnet. However, as the train continues in its path of movement, the sections of resistance 8 are gradually cut out of the 5 circuit and the current strength flowing through such circuit increased so that the valve in the train line air pipe is eventually moved to full open position. Thus, it will be seen that when a train enters the danger 10 zone, the brakes will be applied to the wheels in such manner as to bring the train to a gradual stop thereby eliminating unnecessary vibration of the equipment.

If desired, the resistance sections 8 may 15 be eliminated and each finger 6 tapped onto the respective line of rails 1 so that when the fingers are in active position and a train passes thereover the circuit of the controller will be alternately opened and closed where- 20 by the valve in the train line air pipe will be manipulated after the fashion of the engineer's brake valve and the train line air pressure gradually reduced. In this event it may be found desirable to employ an or- 25 dinary form of turn plug valve in place of the valve herein shown and described.

While I have herein shown and described one preferred form of my invention by way 30 of illustration, I desire to have it understood that I do not limit or confine myself to the precise details of construction herein 35 described and delineated, as modification and variation may be made within the scope of the claims without departing from the spirit of the invention.

I claim:

1. In train stopping apparatus, a resistance grid located on the roadway and including a plurality of sections of resistance 40 connected in series, means for swinging said grid to active position, a train carried mechanism comprising a source of energy, a shoe adapted to ride over said grid in the active position of the latter and contact 45 therewith, and a controller, an electric circuit including said grid, source of energy, shoe and controller in series whereby when the grid is in active position, said shoe will ride over the same and gradually cut the re- 50 sistance out of the circuit so that the controller will operate and bring the train to a gradual stop.

2. In train stopping apparatus, a resistance grid located on the roadway and including a plurality of sections of resistance 55 connected in series, electrically operated means for swinging said grid to active position, a train carried mechanism comprising a source of energy, a shoe adapted to 60 ride over said grid in the active position of the latter and contact therewith, and a controller, an electric circuit including said grid, source of energy, shoe and controller in series whereby when the grid is in active

position, said shoe will ride over the same 65 and gradually cut the resistance out of the circuit so that the controller will operate and bring the train to a gradual stop.

3. In train stopping apparatus, a plurality of contact fingers located on the roadway and suitably spaced apart along the track, a plurality of resistance sections inter- 70 connecting said fingers and connected in series thereby, means for swinging said fingers upwardly simultaneously, a train 75 carried mechanism comprising a source of energy, a shoe adapted to engage said fingers successively in the active position of the latter, and a controller, an electric circuit including said contact fingers, source of en- 80 ergy, shoe and controller in series whereby when the fingers are in active position said shoe will ride over the same and engage the individual fingers successively to gradually energize said controller and bring the train 85 to a stop.

4. In train stopping apparatus, a resistance grid located on the roadway and including a plurality of sections of resistance 90 connected in series, means for swinging said grid to active position, a train carried mechanism comprising a source of energy, a shoe adapted to ride over said grid in the active position thereof, and a controller, an electric circuit including said grid, source of en- 95 ergy, shoe and controller in series whereby when the grid is in active position, said shoe will ride over the same and gradually cut the resistance out of the circuit so that the controller will operate gradually, a valve 100 in the train line air pipe, and connections between said valve and controller.

5. In train stopping apparatus, a resistance grid located on the roadway and including a plurality of sections of resistance 105 connected in series, means for swinging said grid to active position, a train carried mechanism comprising a source of energy, a shoe adapted to ride over said grid in the active position thereof, and a controller, an 110 electric circuit including said grid, source of energy, shoe and controller in series whereby when the grid is in active position, said shoe will ride over the same and gradually cut the resistance out of the circuit so that 115 the controller will operate gradually, a valve in the train line air pipe and adapted when operated initially to effect a service application and subsequently an emergency application, and connections between said valve 120 and controller.

6. In train stopping apparatus, a plurality of contact fingers located on the roadway and suitably spaced apart along the track, a plurality of resistance sections intercon- 125 necting said fingers and connected in series thereby, means for swinging said fingers upwardly simultaneously, a train carried

mechanism comprising a source of energy, a shoe adapted to engage said fingers successively in the active position of the latter, and a controller, an electric circuit including said contact fingers, source of energy, shoe and controller in series whereby when the fingers are in active position said shoe will ride over the same and engage the individual fingers successively to gradually energize

said controller and bring the train to a stop, and a dash pot connected to said controller and adapted to counteract the same.

In testimony whereof I affix my signature in presence of two witnesses.

JACKSON M. ROE.
